UNITED STATES PATENT OFFICE.

CHARLES HENRY DIETERICH, OF COOPERSTOWN, ILLINOIS.

RECEIVER FOR DISCHARGED SHELLS.

SPECIFICATION forming part of Letters Patent No. 663,262, dated December 4, 1900.

Application filed May 8, 1900. Serial No. 15,952. (No model.)

To all whom it may concern:

Be it known that I, CHARLES HENRY DIETERICH, a citizen of the United States, and a resident of Cooperstown, in the county of 5 Brown and State of Illinois, have invented a new and Improved Receiver for Discharged Shells, of which the following is a full, clear, and exact description.

One purpose of the invention is to provide 10 a receiver for shells ejected or extracted from firearms, which receiver is of simple construction and effective in operation, and to so construct the device that it can be readily attached to the frame of a gun or detached 15 therefrom, the shells quickly discharged from the device, and the device compactly closed or folded when it is not required.

A further purpose of the invention is to construct a receiver for empty shells adapted for 20 use in connection with any repeating gun from which the shells are ejected from the side portion of the frame.

The invention consists in the novel construction and combination of the several 25 parts, as will be hereinafter fully set forth, and pointed out in the claims.

Reference is to be had to the accompanying drawings, forming a part of this specification, in which similar characters of reference indicate corresponding parts in both the figures.

Figure 1 is a side elevation of the frame of a repeating firearm and a side elevation of the improved device applied thereto, and Fig. 2 is a perspective view of the device detached 35 from the firearm and in an open position.

A represents the frame of a repeating firearm, B the barrel, and C a magazine. The device consists of a body-frame D, the said frame comprising a horizontal bottom member 10 and upwardly-extending side members 11, the said side members being preferably angular or L-shaped in cross-section, as is shown particularly in Fig. 2. The bottom member 10 of the main or body frame D of 40 the device is provided with a longitudinal slot 12, having a central enlargement. This slot 12 is intended to receive the shank of a button 13, the head of which button is passed through the slot 12 when the device is attached to the frame of the gun, as the button 13 is secured in any suitable or approved manner to the said frame.

In applying the main or body frame D of the device to the frame A of the firearm the body-frame D of the device is placed transversely of the frame A of the firearm, so that the head of the button 13 may readily pass through the slot 12, and after the head of the button has thus passed the slot the body-frame D of the device is brought to its normal position, in which the bottom 10 of the body-frame of the device is parallel with the longitudinal axis of the frame A of the gun, and when the body-frame D is in this position the head of the button 13 will extend across the slot 12.

The extremities of a bow 13^a are pivoted or mounted to turn in the upper portions of the side pieces 11 of the body-frame D of the device, the said extremities of the bow 13^a being passed through the outwardly-extending members of the side pieces of the said body-frame, as shown best in Fig. 2, and in order that the bow 13^a may be held at a right angle to the side pieces 11 of the body-frame of the device and not be drawn downward by the weight of the shells received by the device nuts 13^b or other form of tension devices are provided at the end portions of the bow 13^a.

A second bow 14 is used also in connection with the body-frame D of the device. The ends of this second bow are pivoted in the outwardly-extending members of the side pieces of the said body-frame at a point below the upper bow 13^a and likewise at a point 85 nearer the inner members of the side pieces of the body-frame, as is best shown in Fig. 2. The lower bow 14 extends vertically downward when the upper bow 13^a is placed in a horizontal position, and when the lower bow 14 is in its downwardly-extending position the horizontal member of the said bow is in engagement with the outer face of the lower or horizontal member 10 of the frame D.

A pocket 15, made of any suitable or approved material, a netting being preferably used, is attached to the upper bow 13^a and to the lower bow 14. In attaching this pocket to the two bows the upper mouth portion of the pocket is brought near the pivotal connection of the said upper bow with the body-frame D, the body portion of the bow 13^a extending within the pocket, while the lower portion of the mouth of the pocket 15 is at-

tached to the horizontal member of the lower bow 14. Under this construction when the upper bow 13^a is in its horizontal position (shown in Fig. 2) and the lower bow is in its 5 lower vertical position (shown in the same figure) the mouth 16 of the pocket will be immediately opposite the space between the members of the body-frame and opposite the opening through which the extracted or ejected 10 shells are adapted to pass from the frame of the gun. This pocket is adapted to receive empty shells 17 or shells from which the charge 15 has been fired.

When it is desired to remove the shells from 15 the pocket, the bottom of the pocket is raised to a horizontal position or slightly above a horizontal position, whereupon the lower bow 14 is brought to a horizontal position below the upper bow, and the shells can readily roll out 20 from said pocket and drop upon the ground or into any receptacle placed in position to receive them.

When the device is not required, both of the bows 13^a and 14 are dropped downward, so 25 as to lie close to the body-frame D of the device, and the pocket may be wrapped around that portion of the gun to which the device is applied.

Having thus described my invention, I 30 claim as new and desire to secure by Letters Patent—

1. A receiver for discharged shells, consisting of a frame arranged for attachment to a gun, members pivoted to the said frame, capable of assuming a parallel position or a position at an angle to each other, and a bag or

net attached to the said pivoted members, as described.

2. A receiver for discharged shells, consisting of a frame having means for attachment to a firearm, the said frame comprising a bottom member and side members, bows pivotally attached to the side members of the frame, capable of assuming a position at an angle to each other or of assuming parallel 45 positions, and a bag or net attached to the said bows, the mouth of the bag or net being opposite the space between the members of the frame.

3. In a receiver for discharged shells, a 50 frame comprising a lower member having means for attachment to a firearm, and side members at an angle to the lower member, a bow pivotally connected with the upper portion of the side members of the frame, a second bow pivotally attached to the side members of the frame at a point below and at one side of the upper bow, and a net or pocket the mouth portion of which extends over the upper bow to a point near its pivotal connection with the frame, another portion of the mouth of the said pocket being connected with a member of the lower bow, for the purpose specified.

In testimony whereof I have signed my 6 name to this specification in the presence of two subscribing witnesses.

CHARLES HENRY DIETERICH.
